UNITED STATES PATENT OFFICE

2,182,410

CASEMENT WINDOW SCREEN

Jay Rose, Brooklyn, N. Y., assignor, by mesne assignments, to Wardmore Corporation, a corporation of New York

Application October 23, 1934, Serial No. 749,508

3 Claims. (Cl. 156—14)

This invention relates to casement window screens and is an improvement over the invention set forth in my patent application Serial No. 681,831, filed July 24, 1933, and issued as Patent 5 No. 1,990,206, dated February 5, 1935.

In the above mentioned patent, I provided a novel full length screen for casement windows, the frame of which was of uniform width throughout and which housed the actuating handle and other inwardly extending hardware with which such type of windows are provided, the lower portion of the screen having a screen door to facilitate access to the window latch to open and close the same from the inside. The 10 main feature of this invention is to construct a casement screen of two separable screen sections, namely a lower box-like section for housing the hardware of the casement window, and a narrow upper screen section superposed upon 15 the lower screen section and removably secured thereto. Thus, I am able to save in the cost of frame material due to the difference in depth between the frames of the upper and lower sections, while the detachable connection between 20 the two screen sections, facilitates positioning the screen sections one against the other, for ease in handling and assures a more compact arrangement for shipping and storing purposes.

Another feature of the invention resides in 30 a casement window screen in which the upper screen section is of a lesser depth than the box-like lower frame section to prevent interference of the raising and lowering of the window shade or other like window drapes.

With these and other objects in view, the invention resides in the detailed construction, combination and arrangement of parts, the essential features of which are hereinafter pointed out in the appended claims and are illustrated in the 35 accompanying drawing, in which:

Figure 1 is a perspective view of my improved screen set up for use.

Figure 2 is an enlarged rear elevational view.

Figure 3 is a side elevational view showing the 45 screen sections folded positioned one against the other.

Figure 4 is a detail vertical sectional view on the line 4—4 of Figure 2.

Figure 5 is a detail horizontal sectional view 50 through the screen attaching means.

Figure 6 is a view similar to Figure 5 but showing a modified form of screen attaching means.

Figure 7 is a detail vertical sectional view 55

through a modified form of fastening means between the upper and lower screen sections.

Referring to the drawing by reference characters, the numeral 10 designates my improved metal casement window screen in its entirety 5 and which is of a size to fit against the weather flange of a window casement frame to close a window opening of a particular size. The screen 10 includes a box-like lower screen section 11 which is of a depth greater than the relatively 10 narrow upper screen section 12, which upper screen section is superposed relative to the lower screen section and the said screen sections are detachably connected together in a manner and for the purpose to be hereinafter explained. 15

The lower screen section 11 includes a metal box-like frame 13 of rectangular configuration and the rear side of the frame is provided with inwardly extending flanges 14 around its four sides. Hinged to the front of the box-like frame 20 13 as at 15 is a screen door 16, the same being provided with knob and catch means 17 for securing the door in closed position. The box-like section 11 when in use, fits against the weather flange 18 of a casement window frame 25 with the side flanges 14 fitting flat against the casement flange to close the space therebetween as best seen in Figure 5 of the drawing. In the preferred embodiment of the screen attaching means, I provide key hole shaped slots 19 in the 30 side flanges 14 which fit upon headed studs or screws 20 extending inwardly from the casement flange 18. If desired, other forms of attaching means may be resorted to as shown in Figure 6 wherein metal resilient clips 21 fit over the free 35 edges of the screen frame flanges 14 and the casement weather flange 18.

The upper screen section 12 includes a metal frame 22 which is also rectangular in configuration and although the frame 22 is shown with a 40 covering of wire screen 23, this section may also be provided with a screen door as is the lower section to facilitate washing of the upper portions of the casement window without necessitating the removal of the upper screen section from the casement frame. 45

The screen frame 22 is provided with relatively narrow side flanges 24 compared with the width of the sides of the box-like frame 13 and their rear edges terminate on a plane substantially 50 in alignment with the flanges 14 of the lower screen section. The top and opposite sides of the rear edges of the flanges 24 carry a yieldable weather strip 25 which may be in the form of rubber, felt or the like, and which weather strip- 55

ping tightly abuts the upper portion of the weather flange 18 of the casement frame to close the space between the upper screen section and the casement frame.

5 In the preferred embodiment of the invention, the upper and lower screen sections are hinged together at their meeting sides as at 26, the hinged barrels between the two sections receiving removable hinge pins 27 to facilitate 10 separation of the hinges and disconnection of the two screen sections. The hinge means also permits the two screen sections to fold one against the other as illustrated in Figure 3 of the drawing to lend compactness to the screen when not 15 in use for shipping and storage purposes.

When the screen is in extended position as shown in Figure 1, and the lower section is attached to the casement flange of the casement window, the lower box-like screen section 11 20 houses the inwardly extending hardware of the casement window, while the door 16 facilitates access to the hardware for the opening and closing of the window.

In Figure 7 of the drawing, there is shown a 25 modified form wherein the bottom flange 24 of the upper screen section 22 is provided with openings 25 which register with openings 26 in the top of the box-like frame 13, while bolts 27 extend inwardly through the aligned openings 30 and receive clamping thumb nuts 28. This form of removable fastening may be used in lieu of the hinge means shown in the preferred form, and facilitates the separation of the upper and 35 lower screen sections for the ease in handling and the compact placing of one screen section against the other during shipment and storage.

While I have shown and described, what I deem to be the most practical embodiments of my invention, I wish it to be understood that such

changes as come within the scope of the appended claims may be resorted to if desired.

Having thus described the invention, what I claim as new and desire to secure by Letters Patent of the United States, is:—

5 1. In a casement window screen, a lower box-like screen section having a door in the front thereof, and an upper screen section resting upon the top of the lower screen section and stepped back from the front thereof and flush with the rear thereof, and fastening means removably securing the meeting sides of said screen sections together, said means preventing inward collapsing of the sections.

15 2. A window screen comprising a lower box-like section provided with a screen door at its front side, an upper screen section of approximately equal area but of less depth than the lower section, means for removably securing the two sections together in superposed relation with their rear faces in alignment, and means cooperating with only one of said sections for holding both sections in place against the inside face of a window frame and thereby maintaining said alignment.

20 3. A screen frame for a metal casement window, comprising a relatively deep frame having a screen door at one side, the other side being adapted to be fitted against the side of a weather flange of a casement window, the depth of the frame being sufficient to extend beyond the window hardware including its handle, an extension frame of a relatively shallow section adapted to be placed on top of the main frame, the combined height of the main and extension frames 30 corresponding to the full height of the window, and means to detachably and rigidly connect the two frames together.

35 JAY ROSE.
